MULE SPINNING MACHINE

Robert A. Gard, Charlton City, Mass.

Application January 27, 1941, Serial No. 376,156

12 Claims. (Cl. 57—46)

This invention relates to improvements in mule spinning machines and has particular reference to improved means and method of winding yarn onto the bobbins of such machines.

One of the principal objects of the invention is to provide means and method of controlling the windings of yarn onto the bobbins of a mule spinning machine so as to provide a relatively short substantially continuously tapered wind at the start of said bobbins.

Another object is to provide novel means and method of controlling the shape of windings adjacent the head of the bobbins of a mule spinning machine by adjustment of the builder rail adjacent the rear thereof to alter the extent of movement of the mechanism of said machine which controls the position and amount of initial windings which are placed adjacent the head of the bobbins at the start of the winding operation and to provide means adjacent the front of the builder rail for compensating for the extent of adjustment of the rear of the builder rail in order to accomplish the above result and to insure the accurate positioning of the initial windings on the bobbins adjacent the heads thereof.

Another object is to provide an attachment for use in combination with a device for controlling the initial windings on the bobbins which will insure that the guide faller wires will accurately locate the initial windings in proper position on the bobbins.

Another object is to provide adjustable builder rail supporting means which will locate the initial windings of yarn onto the bobbins adjacent the head of the bobbins and simultaneously cause the windings to assume a short tapered shape adjacent said heads.

Another object is to provide improved means and method of quickly and easily adjusting machines of the above character so as to insure the production of the tapered initial windings adjacent the head of the bobbins whereby the percentage of yarn wastage which has hitherto been inevitable with automatic type weaving machines is greatly reduced.

Other objects and advantages of the invention will become apparent from the following description taken in connection with the accompanying drawings and it will be apparent that many changes may be made in the details of construction, arrangement of parts and methods shown and described without departing from the spirit of the invention as expressed in the accompanying claims: I, therefore, do not wish to be limited to the exact details and steps of the methods shown

and described as the preferred forms only have been given by way of illustration:

Referring to the drawings:

Fig. I is a fragmentary diagrammatical perspective view of the machine embodying the invention;

Fig. II is a fragmentary diagrammatic side elevation showing the relation of the device embodying the invention with the associated operating mechanism of the machine to which the invention is applied and which accomplishes the results desired;

Fig. III is an enlarged fragmentary perspective view of the mechanism for raising and lowering the rear of the builder rail for controlling the initial desired tapered windings of yarn on the bobbins.

Fig. IV is a view generally similar to Fig. III showing the mechanism for compensating for the shift of position of the front of the builder rail due to the rear adjustment thereof whereby the initial windings on the bobbins may be accurately positioned thereon.

Fig. V is an enlarged fragmentary sectional view taken as on line V—V and looking in the direction indicated by the arrows;

Fig. VI is an enlarged fragmentary sectional view taken as on line VI—VI of Fig. IV and looking in the direction indicated by the arrows;

Fig. VII is a fragmentary sectional view taken as on line VII—VII of Fig. V and looking in the direction indicated by the arrows;

Fig. VIII is a fragmentary sectional view taken as on line VIII—VIII of Fig. VI and looking in the direction indicated by the arrows; and

Fig. IX is a fragmentary side view showing the head of the bobbin and the characteristics of the windings as formed by the improved means and method of the invention.

The invention relates particularly to the provision of attachments for use with mule spinning machines whereby differently controlled windings of yarn on the bobbins at the start of the winding operation may be formed.

It has been usual in the past, particularly for bobbins which are to be used with an automatic type weaving machine wherein the bobbins are automatically inserted in and ejected from the weaving shuttles during the operation of the machine, to build up the windings at the start or adjacent the head of the bobbin so as to insure the provision of sufficient yarn to enable the shuttles to travel across the lathe or weaving head of the weaving machine and back after the automatic ejecting mechanism of such weaving machines

has been tripped and rendered ready to operate by a feeler which engages the wall of the bobbin just prior to the ejecting operation.

With the usual method of providing sufficient yarn at the head of the bobbin, to enable the accomplishing of the above result, the windings at the head of the bobbin were so bunched that the yarn could not be drawn freely from the bobbin, causing undue breakage and resulting in excess wastage of yarn when the bobbins were ejected.

Many different devices have been employed for providing means for building up the yarn at the head of the bobbin, such as separate tapered members, which were attached to the upper surface of the builder rail, or means for holding the faller arm or faller arm roll away from the rail adjacent the rear end thereof at the start of the winding operation. Such prior art arrangements caused a bunched, tight winding to be formed, causing the above undesired results of accidental breakage and excessive waste of yarn.

One of the prime objects, therefore, of the invention is to overcome the above difficulties by providing gradually substantially continuously tapered windings adjacent the head of the bobbin so that when the yarn is drawn from the bobbin during the weaving operation, the yarn will feed freely from the bobbin when a point is reached wherein the feeler of the automatic ejecting mechanism engages the wall of the bobbin and the shuttle then makes its last trip across the operating head or lathe of the weaving machine back into the shuttle box from which the bobbin is ejected and a new bobbin is automatically placed in the shuttle. The gradually tapered windings are such that they allow the yarn to be drawn freely from the bobbin and thereby greatly reduce the tendency of the yarn to break as the end of the windings on the bobbin is approached prior to ejection and allows more of the yarn to be drawn from the bobbin with the result that a less amount of yarn remains on the bobbin when ejected from the shuttle and thereby greatly reduces yarn wastage.

The method of operation of the mule spinning machine resulting from the device embodying the invention also greatly increases the efficiency of operation and production of such machines as it puts less strain on the yarn during the operation of building up the short tapered wind and thereby greatly reduces breakage of the yarn during said winding operation. The improved devices are such that the adjustments for bringing about the above result may be made separately or independently of the builder rail or shoe adjustments. None of the operating and adjustable parts of the present devices require detachment and may be quickly and easily adjusted without disturbing the general adjustments and operation of such machines.

Referring more particularly to the drawings wherein like characters of reference designate like parts throughout the several views the device to which the invention is embodied comprises a carriage 1 having a plurality of spindles 2 thereon for supporting the bobbins 3. The spindles 2 are supported for rotation by means of a belt or the like 4 connected with a pulley 5 on the spindles and with a rotating drum or the like not shown. The rotation of the spindles 2 is by the usual means known in the art. The carriage 1 is provided with wheels 6 which engage suitable rails 7 for longitudinal movement toward and away from the supporting means

8 on which the spools 9 are mounted. The spools 9 have the yarn 10 wound thereon. The said yarn is adapted to be drawn through suitable rollers 11 and 12 and is connected to the spindles 2 adjacent the heads of the bobbins. This is a conventional function.

Suitable guide wires, such as the guide faller wire 13 and tension faller wire 14, are provided for controlling the position of the windings of the ends 15 on the bobbins 3 and, also, for maintaining the desired tension on the ends during said winding.

The guide faller wire and tension faller wire are carried by suitable hook-like supporting arms 16 and 17 respectively attached to shafts 18 and 19. The said shafts are rotatably mounted on suitable bearings carried by the supports 21 and 22 attached to the front of the carriage 1. The shaft 18, to which the arms 16, carrying the guide faller wire 13 is attached, is rotated to raise and lower the said guide faller wire by means of a faller arm 23. This faller arm is raised or lowered through its connection with a suitable roller 24 which engages a builder rail 25. The builder rail 25 is attached to slide blocks 26 and 27 slidably supported in upright guide members 28 and 29 carried by suitable base plates 30 and 31 located in the front and rear of the machine, see Figs. I to IV inclusive. The guide blocks 26 and 27 are secured to the rail by connection bolts 32 and 33 which extend through the guide blocks 26 and 27 and through suitable bearings 34 and 35 internally of the front and rear end portions of the guide rail 25, see Figs. V and VI. The guide bolt 33 has a cam member 36 attached thereto which is adapted to engage the inclined surface 37 of a rear builder shoe 38. The cam 36 has a riser portion 39 which is adapted to be rotated in engagement with the cam surface 37 of the shoe 38 by means of a lever 40 connected to the bolt 33 by means of a lock screw or the like 41. The lever 40 is connected by a link member 42 to an upright 43 carried by a tie member 44 by means of which it is connected to a rod 45. The rod 45 extends forwardly and is connected at 46 adjacent the lower end of a rock lever 47. The rock lever 47 is pivotally attached at 48 to an upright 49 carried by the base plate 30. The rock lever 47 is secured in adjusted position by means of a spring pressed plunger 50 which engages in suitable recesses 51 formed in the base plate 30 for locking the rock lever in forward or rearward adjusted position. A suitable grip lever 52 pivotally attached to the rock lever at 53 is adapted to raise the spring pressed plunger 50 to disengaged position with respect to the openings 51 in the base plate whereby the rock lever may be swung on its pivot 48 to draw the rod 45 forwardly or rearwardly as desired. When the rock lever 47 is moved in a rearward direction, as indicated by the arrow 54, the rod 45 is drawn in a forward direction. This forward movement causes the upright 43 to draw the link member 42 forwardly and simultaneously rock the lever 40 in said forward direction and move the high spot 39 of the cam 36 down into engagement with the inclined abutment surface 37 of the builder shoe 38. This causes the slide block 27 to move upwardly of the slideway in the upright 29 and also causes the rear end of the builder rail 25 to raise the amount introduced by the throw of the cam 39. It is apparent that the extent of movement of the rock lever 47 in a rearward direction controls the extent of raising of the rear of the

builder rail 25. The builder rail 25 is thereby moved to different inclined positions depending upon the extent of movement of the cam 36. When the carriage 1 is moved forwardly longitudinally of the rails 7 under the guidance of the wheels 6, which support the carriage 1, the roller 24 which engages the builder rail 25 will cause the faller arm 23 to be raised or lowered the amount introduced by the difference of pitch of the upper contact surface of the builder rail 25. The carriage is moved forwardly by suitable means which is conventional in the art and the speed of movement is also controlled by the usual conventional speed regulating mechanism of such machines. During the operation of the machine the carriage which is moved rearwardly and forwardly, as is usual in the art, and the mechanism for accomplishing this result is of the usual conventional prior art type which may be controlled to regulate the speed and extent of movement of the carriage to accomplish the results desired.

The above described mechanism is of the conventional known type in the art and for this reason is not shown. A thorough description of one of the machines with which the device embodying the invention may be used can be found in a publication on "High speed mules" by Johnson & Bassett, Incorporated, Worcester, Massachusetts, which description is of the machine embodying the invention and is, therefore, part of the disclosure relied upon in this specification. The length of the rod 45 may be shortened or lengthened through the provision of a suitable turn buckle 55, as illustrated in Fig. IV.

It is to be seen, therefore, that when the upper portion of the lever 47 is moved in a rearward direction the lower end 46, to which the rod 45 is attached, will draw the said rod 45 in a forward direction causing the cam 39 to raise the rear end of the builder rail 25 and vice versa.

It is to be understood that various different arrangements may be provided for controlling the extent of raising or tilt of the builder rail. The amount of lift or tilt is determined by the characteristics or the type of winding desired adjacent the head of the bobbins and it is through this adjustment of the height and tilt of the builder rail from adjacent the rear end thereof at the start of the winding operation which produces the substantially continuously short tapered winding.

The tapered windings which result from the builder rail adjustment and associated operating mechanism for bringing about this adjustment, as shown at 56 in Fig. IX, is of a cone shape with the bottom of the cone adjacent the head 57 of the bobbin tapering upwardly and blending with the body of the bobbin 3, at a point upwardly of said bobbin ranging between $\frac{3}{4}$ to $1\frac{1}{2}$ " from the upper surface 58 depending upon the adjustment of the improved mechanism set forth above for controlling the characteristics of the windings.

The tapered windings result broadly from forming the first windings relatively close and with slightly more windings adjacent the bottom or head of the bobbin and gradually decreasing and slightly spacing the windings upwardly of the bobbin until the uppermost point or limit to which the tapered windings are to be formed is reached. The windings are then directed downwardly from said point and are caused to be spread apart considerably as they progress downwardly toward the head of the bobbin. The

next upward windings are in close relation with each other and simulate the first upward windings. This operation is repeated until the gradually tapered windings of the amount desired are formed adjacent the base or head of the bobbin, as illustrated in Figs. IX. It is to be understood that the spread of the windings, the movement of the carriage and the rotation of the bobbin 3 is so controlled together with the movement of the guide faller and tension wires 13 and 14 respectively as to accomplish the results desired, and it is particularly pointed out that the tapered windings described above result from the altering of the pitch or inclination of the upper surface of the builder rail 25, as accomplished by the movement imparted to the rear of the builder rail 25 by the cam member 36.

The builder rail 25 has a so-called high point 59 at which point the upper surface of said rail, as illustrated at 60, is inclined in a downward and forward direction the purpose of which will be described more in detail hereinafter. It is quite obvious that when the rear of the builder rail is raised the high point 59 of said rail will simultaneously be raised proportionately. This normally would throw the guide faller wire 13 and tension faller wire 14 out of desired relation with the bobbin 3. To compensate for this off adjusted position which results from the raising of the rear end of the builder rail there is provided a cam surface 61 on the connection bolt 33. This may best be seen in Figs. VI and VIII. The bolt 33 is supported for rotation internally of the slide block 26 and bearing 35 and is provided adjacent the end thereof opposite the builder rail 25 with a lever 62. The said lever 62, as best shown in Figs. II and IV, is connected by a link member 63 to an upright 64 carried by a clamp block 65 attached to the rod 45. The area of the connection bolt 33 at which the cam surface 61 is located is adapted to engage the upper contour surface 66 of the forward builder shoe 67. The said shoe 67 having the bolt 33 resting thereon is adapted to support the slide block 26 to which the forward end of the builder rail 25 is attached at its normal position of use. When the rear end of the builder rail 25, however, is raised by the cam member 36, as set forth above, and the high point 59 of said rail is simultaneously raised proportionately through the forward movement of the tie rod 45, as results through the movement imparted thereto by the rock lever 47, the upright 64 through its link connection 63 with the lever 62 will simultaneously rotate the connection bolt 33 and cause the recessed cam surface 61 to move into engagement with the supporting surface 66 of the builder shoe 67. This causes the block 26 to move downwardly proportionately with the amount of recession of the cam surface 61, which amount, is sufficient to compensate for the amount which the high point 59 of the builder rail 25 is raised when the rear end thereof is raised by the cam member 36. This, therefore, repositions the guide faller wire 13 and tension faller wire 14 in proper relation with the bobbins 3 so that the windings will start at their proper position adjacent the head 57 of the bobbin. The builder shoes 38 and 67 are slidably supported on their respective base plates 30 and 31. The said builder shoes are connected by a tie rod 68 whereby sliding movement imparted to one of said builder shoes will simultaneously cause the other of said builder shoes to move proportionately. The said builder shoes are ad-

justed by a suitable screw member 69 supported in a bearing 70 carried by the bed plate 30 and threadedly connected with the connecting blocks 71 carried by the tie rod 68. This is part of the conventional mechanism of such machines. The adjustment is accomplished through the coupling of a suitable crank member with the end 72 of the member 69.

The adjustment of parts and the operation of the machine for bringing about the results desired is substantially as follows:

It is assumed that the doffing has been completed and that the ends 15 of the yarn to be wound on the bobbins is in initial positional relation therewith preparatory to starting the machine. The carriage 1 is now over the main face 73 of the builder rail 25 as the carriage 1 is now in beyond the high point 59 of said rail according to the conventional operation of the machine. The face 73 is normally inclined rearwardly and downwardly. This inclination is such as to cause the faller arm roll 24 and the said arm 23 to drop gradually as the carriage 1 completes its inward motion. This causes the guide faller wire 13 operated by the faller arm 23 to rise a controlled amount determined by the length of travel of the carriage 1 along the face 73 and the pitch of the downward inclination of said face. This is a normal setting for completing the building up of the windings on the bobbin after the desired short windings are formed adjacent the head of the bobbins.

In carrying out the present invention and to form the initial short tapered windings adjacent the head of the bobbins, the rear end of the builder rail 25 is elevated a controlled amount. This is accomplished by the adjustment of the lever 40 in a forward direction which rotates the high spot 39 of the cam 36 into engagement with the surface 37 of the builder shoe 38. This is accomplished through the manipulation of the upper portion of the rock lever 47 in a rearward direction as illustrated in Figs. I, II and IV and the extent of adjustment is such as to change the pitch of inclination of the face 73 the proper amount to cause the guide faller wires 13 to move upwardly of the bobbins 3 a restricted controlled amount of approximately $\frac{3}{4}$ to $1\frac{1}{2}$ ", more or less, according to the setting brought about by the rock lever 47 when the carriage 1 is first moved inwardly. It is to be noted that the front end of the builder rail, that is, the inclination of the face 60 adjacent the front of the rail is changed or slightly increased from its normal angle by said adjustment.

Simultaneous to the movement of the high spot 39 of the cam member 36 into engagement with the surface 37 of the builder shoe 38 the recessed cam surface 61 of the bolt 33 is moved into engagement with the contact surface 66 of the forward builder shoe 67. This compensates for the upward movement of the high point 59 of the rail which takes place during the raising of the rear end of the rail and the amount of compensation is such as to cause the guide faller wire 13 and tension faller wire 14 to return to desired positional relation with the bobbins 3 and they will thereby cause the windings to start on the bobbins at the proper position adjacent the heads thereof.

As stated above, as the guide faller wire 13 moves upwardly of the bobbin, when the carriage 1 moves inwardly, as controlled by the pitch of the surfaces 60 and 73 respectfully of the builder rail, the windings on the bobbin dur-

ing this upward movement of the guide faller wire 13 will be relatively close at the start and will separate slightly as the guide faller wire approaches the full extent of its upward and restricted movement as determined by the pitch of the surfaces 60 and 73. The faller arm 23 is then disengaged from the roller 24, causing the guide and tension wires 13 and 14 to move upwardly and simultaneously to wind loose yarn to the top end of the bobbin at which position the bobbins cease to rotate.

The carriage 1 is then ready to move outwardly or forwardly with the usual mechanism functioning to feed the loose yarn 10 from the spools 9. As the loose yarn is fed from the spool, the outward movement of the carriage 1 draws and twists the yarn. This twisting is caused by simultaneous rotation of the bobbins.

Due to the fact that the faller arm 23 and roller 24 are disengaged, the guide and tension wires 13 and 14 remain stationary adjacent the upper ends of the bobbins and thereby prevent any winding of yarn on said bobbins. The rotation of the bobbins, therefore, merely twists the yarn.

When the carriage 1 nears the limit of its outward or forward movement the twisting operation is completed by further rotation of the bobbins a controlled amount. When the twisting is completed, and before the winding operation can begin, the small amount of yarn between the top of the bobbin and the yarn already on the bobbin must be unwound. To do this the spindles 2 carrying the bobbins must be revolved in the opposite direction for a few turns. This motion is termed the backing off and is the usual motion imparted in the art of spinning.

The tension and guide faller wires 13 and 14 are then operated by their usual known operating mechanism and simultaneously move the guide faller wire 13 downwardly to take up this slack of yarn removed from the bobbin during the backing off. The guide wire 13 moves downwardly to a point adjacent the upper end of the first winding.

As the guide wire 13 goes down the faller arm 23 goes up until it reaches a point where it is moved into interlocked relation with the faller arm roll 24. This engagement takes place after the twisting operation has been completed and at the position at which the carriage is located as the result of its being eased in during the twisting operation. This interlocking of the faller arm with the faller roll, at this location, takes place through the usual mechanism provided with such machines. When the faller arm and roll are interlocked, the roll will be resting on the inclined surface 60 adjacent the front end of the builder rail 25.

The machine is then ready to start its second wind. As the carriage 1 moves inwardly the faller arm roll 24, engaging the sharply inclined surface 60 at the front end of the builder rail, causes the guide faller wire 13 to move downwardly quite rapidly causing the windings in the downward direction of the bobbins to be spread considerably until the lowermost position is reached. This lowermost position is reached as the faller arm roll 24 rides over the end 59 of the sharply inclined surface 60 onto the main surface 73 of the builder rail. The main surface from this point, due to the adjustment brought about by raising the rear end of the builder rail through rotation of the cam 36 to move the high spot 39 thereof into en-

gagement with the inclined surface 37, will be slightly inclined downwardly a controlled amount as previously described above.

This causes the faller arm 23 to move downwardly and move the guide faller wire 13 gradually upwardly. At the start of this upward movement, the carriage moving mechanism is such that the carriage 1 moves in slowly causing the guide faller wire 13 to likewise move slowly upwardly. Due to the fact that the bobbins 3 are simultaneously being continually rotated in the direction of winding, more windings will be made on the bobbin adjacent the bottom. These windings are gradually directed upwardly of the bobbin as the carriage moves in and as the guide wire 13 simultaneously moves upwardly. The speed of the carriage gradually increases as it continues to move in and thereby causes the guide wire 13, operated by the downward movement of the faller arm 23, as brought about by the degree of rearward inclination of the main face 73 adjacent the innermost end thereof, to move upwardly with more speed and thereby reduce the windings and increase the space between said windings. The said spaced windings continue until the carriage reaches its innermost position.

This operation is repeated again with the result that cone shaped windings 56, as shown in Fig. IX, are formed adjacent the head 57 of the bobbins. This operation is repeated until the desired amount of short windings are formed. There may be more or less short windings put on if desired.

The new mechanism is then disengaged by operation of the rock lever 41 in the opposite direction to move the high spot 39 of the cam 36 upwardly out of engagement with the inclined surface 37 and thereby allow the rear end of the rail 25 to drop to its normal position of use. The machine is then operated to complete the usual windings which fills the bobbins.

The bobbins are then removed and transferred for use in weaving looms. The looms with which such bobbins are used, are of the usual automatic type wherein the bobbins are automatically positioned in and ejected from the weaving shuttles during the operation of the loom.

With the tapered wind 56 adjacent the head 57 of the bobbin, as made by the present invention, only a relatively small amount of yarn remains on the bobbin when ejected from the shuttle. This is due to the fact that the yarn is allowed to be removed from the bobbin to a point adjacent the base of the taper prior to the operation of a device known in the art as a feeler 74, which causes the ejecting mechanism to function. The feeler does not operate until it engages the bare solid side wall of the bobbin and this engagement only takes place after the yarn has been fully removed from the area 75 which aligns with the feeler. When the area has been stripped of its windings, the feeler operates but the ejection does not take place until the shuttle travels across the lathe or head of the loom and returns back to the shuttle box at which the bobbin is ejected from the shuttle.

It is apparent, therefore, that sufficient windings must be on the bobbin to permit this to take place. The tapered winding, as made by the present invention, is such that it not only provides the necessary amount of windings, but also allows the said yarn to be easily drawn

from the bobbin. The tapered windings are such that accidental breaking of the yarn, prior to the ejection of the bobbin, is substantially eliminated and causes only a slight amount of yarn to remain on the bobbin and thereby eliminates undesired waste. This latter result is one of the outstanding features of the invention and overcomes the difficulties encountered with most prior art arrangements.

The inclination of the face 73, when in its normal prior art position of general use, is relatively steep as compared with the change of inclination brought about according to the present invention. The normal inclination has been such as to cause the guide faller wire 13 to raise quite quickly and form substantially uniformly distributed windings throughout its span of movement. The inclination of the face 60, when in its normal prior art position of general use, is relatively less than when changed according to the present invention so that the usual windings in the downward direction were normally greater and closer than those resulting from the present invention. The increase of inclination of said face 60 resulting from the arrangement embodying the invention, reduces and increases the spacing of said downward windings due to the relatively quick rise and resulting quick drop of the guide faller wire which controls the position of the windings on the bobbin.

The windings resulting from the arrangement embodying the invention will be less at the top of the taper because the guide faller wire moves down with greater speed, due to the increased incline of the face 60 and more windings are formed at the bottom or base of the taper because of the relatively slight inclination of the face 73 which has been decreased by the device embodying the invention, as stated above, and through the tendency of said slight inclination to cause the guide faller wire to move upwardly much more slowly at the start, resulting in more windings being formed at the base of the bobbin. This is because of the relatively slow reversing movement of the guide faller wire brought about by the traversing of the high point 59 onto the face 73 at the start of the upward windings and the speed of inward movement of the carriage 1 is relatively slow at the start, as stated above. This slow inward movement of the carriage, and the increasing of the speed of the carriage after it has started its inward movement, combined with the decreased speed of upward movement of the guide faller wire, as brought about by the reducing of the inclination of the builder rail, all contribute to the forming of the short tapered wind 2. It is to be understood that although more windings are being formed at the base of the bobbin, said windings are gradually in an upward direction so that when the last of the windings are being removed from the bobbin in the weaving loom, the said yarn will flow freely from the bobbin. The angle of the face 60 may be changed, if desired, by adjustment of the screw or the like 76.

Due to the fact, therefore, that the windings progress upwardly a substantially continuous taper wind will be formed.

From the foregoing description it will be seen that simple, efficient and economical means and method have been provided for accomplishing all of the objects and advantages of the invention.

Having described my invention, I claim:

1. In a device of the character described the combination of a builder rail having its guide

faces supported at given inclinations; means for lifting one end of said guide rail relative to a given point along said guide rail to alter said inclinations and means adjacent the opposite end of said guide rail for lowering said given point an amount sufficient to compensate for the amount said given point is lifted when said first end of said guide rail is lifted.

2. In a device of the character described the combination of a guide rail supported with its guide faces at given inclinations, means adjacent the rear end of said guide rail for lifting said guide rail and a given point along said guide rail to alter the inclinations of said guide faces, manually operable means adjacent the front end of said guide rail for operating the means adjacent the rear end of said guide rail for lifting said rear end and means adjacent the front end of said guide rail interconnected and operable with the manually operable means for lowering said given point along said guide rail an amount sufficient to compensate for the amount said given point is raised through the raising of the rear end of the guide rail.

3. In a device of the character described the combination of a guide rail supported with its guide faces at given inclinations, cam means adjacent the rear end of said guide rail for lifting said guide rail a given amount to alter the inclinations of said guide faces with said lifting causing a given point along said guide rail to be simultaneously lifted, remote control means for operating said cam means and means interconnected with and operable by said remote control means for lowering said given point along said guide rail an amount sufficient to compensate for the amount said given point is raised through the raising of the rear end of said guide rail.

4. In a device of the character described the combination of a guide rail supported with its guide faces at given inclinations, eccentric means interconnected with the guide rail adjacent the rear end thereof for rotation about an axis within the confines of said eccentric means, contact means in engagement with said eccentric means and means for rotating said eccentric means to engage a high point thereon with the contact means for raising the rear end of said rail to alter the inclinations of said guide faces.

5. In a device of the character described the combination of a guide rail supported with its guide faces at given inclinations, eccentric means interconnected with the guide rail adjacent the rear end thereof, contact means in engagement with said eccentric means, means for rotating said eccentric means to engage a high point thereon with the contact means for raising the rear end of said rail to alter the inclinations of said guide faces and to simultaneously cause a given point along said guide faces to be raised and means adjacent the opposite end of said guide rail for lowering said opposite end and said given point an amount sufficient to compensate for the amount said given point has been raised.

6. In a device of the character described the combination of a guide rail supported with its guide faces at given inclinations, eccentric means interconnected with the guide rail adjacent the rear end thereof, contact means in engagement with said eccentric means, means for rotating said eccentric means to engage a high point thereon with the contact means for raising the rear end of said rail to alter the inclinations of said guide faces and to simultaneously cause a given point along said guide faces to be raised

and eccentric means adjacent the opposite end of said guide rail for lowering said opposite end and said given point an amount sufficient to compensate for the amount said given point has previously been raised.

7. A device of the character described for use in combination with the guide rail of spinning machines, said device comprising means adapted to be supported adjacent the rear end of the guide rail for raising said rear end and for simultaneously causing a given point along the guide faces of said guide rail to be simultaneously raised and means adapted to be supported adjacent the front end of said guide rail for lowering said front end and said given point an amount sufficient to compensate for the amount said given point is raised through the raising of the lower end thereof during the use of the device.

20 8. In a device of the character described the combination of a guide rail for controlling the winding mechanism of said device, said guide rail having a guide face thereon supported at a given inclination, a contact member adjacent the rear end of said guide rail, eccentric means associated with said guide rail and having a portion for engaging said contact member, remote control means for operating said eccentric means to raise said guide rail an amount sufficient to alter the inclination of said guide face, and for simultaneously raising a given point along said guide face and means operably connected with said remote control means located adjacent the forward end of said guide rail for lowering said forward end and said given point an amount sufficient to compensate for the amount said given point is raised through the raising of the rear end of said guide rail.

25 9. In a device of the character described the combination of a guide rail for controlling the winding mechanism of said device, said guide rail having a guide face thereon supported at a given inclination, a contact member adjacent the rear end of said guide rail, eccentric means associated with said guide rail and having a portion for engaging said contact member, remote control means for operating said eccentric means to raise said guide rail an amount sufficient to alter the inclination of said guide face, and for simultaneously raising a given point along said guide face and eccentric means operably connected with said remote control means located adjacent the forward end of said guide rail for lowering said forward end and said given point an amount sufficient to compensate for the amount said given point is raised through the raising of the rear end of said guide rail.

30 10. In a device of the character described the combination of a guide rail for controlling the winding mechanism of said device, said guide rail having a guide face thereon supported at a given inclination, a contact member adjacent the rear end of said guide rail, eccentric means associated with said guide rail and having a portion for engaging said contact member, remote control means for operating said eccentric means to raise said guide rail an amount sufficient to alter the inclination of said guide face, and for simultaneously raising a given point along said guide face, contact means adjacent the forward end of said guide rail and eccentric means in engagement with said contact means and operably connected with said guide rail and with said remote control means for lowering said forward end and said given point an amount sufficient to

compensate for the amount said given point is raised through the raising of the rear end of said guide rail.

11. A device for use in combination with the guide rail of a spinning machine, said device comprising in part a cam and lever member adapted to be operably associated with one end of said guide rail and with a contact member located adjacent said end of said guide rail, an eccentric member and lever adapted to be associated with the opposite end of said guide rail and with a contact member adjacent said opposite end and means for interconnecting said levers for imparting simultaneous movement thereto.

12. A device for use in combination with the guide rail of a spinning machine, said device comprising in part a cam and lever member adapted to be operably associated with one end of said guide rail and with a contact member located adjacent said end of said guide rail, an eccentric member and lever adapted to be associated with the opposite end of said guide rail and with a contact member adjacent said opposite end and means operably connecting said levers and embodying a rock lever for remotely imparting simultaneous movement to said levers and to the respective associated eccentric means.
